(57) **CLAIM**

The ornamental design for a tire tread, as shown and described.

DESCRIPTION

FIG. 1 is a perspective view of a tire tread in accordance with the invention;

FIG. 2 is an enlarged fragmentary view of the upper portion of the tire tread of FIG. 1.

FIG. 3 is a front elevation view thereof;

FIG. 4 is a side elevation view thereof; and,

FIG. 5 is an enlarged fragmentary view of the upper portion of the tire tread of FIG. 3.

The broken lines depict environmental subject matter only and form no part of the claimed design.
